UNITED STATES PATENT OFFICE.

HENRY F. WHEELER, OF BOSTON, ASSIGNOR TO JOHN P. LOVELL, OF WEYMOUTH, MASSACHUSETTS.

BREECH-LOADING FIRE-ARM.

SPECIFICATION forming part of Letters Patent No. 233,901, dated November 2, 1880.

Application filed February 2, 1880.

To all whom it may concern:

Be it known that I, HENRY F. WHEELER, of Boston, county of Suffolk, State of Massachusetts, have invented an Improvement in 5 Breech-Loading Guns, of which the following description, in connection with the accompanying drawings, is a specification.

This invention relates to breech-loading guns, and has for its object such a construction of the parts as to prevent the hammer from being raised when the barrel is nearly in firing position, or until after the barrel of the gun has been locked by the locking device, which holds it securely in proper firing position in the breech-frame.

My invention consists, essentially, in the employment, with a barrel-locking device, of a hammer-controlling device, which is made movable by or through, and in unison with, the 20 said barrel-locking device, and which is so located with relation to the hammer that the latter cannot be raised when the barrel-locking device is partially thrown backward, as it would be were the barrel almost in position to 25 be locked and held positively in position for firing.

In a gun containing this my invention there is no possibility of exploding the cartridge by the firing-pin until the barrel is thoroughly 30 locked, and accident from such cause, not now infrequent, cannot happen.

The hammer-controlling device is herein shown as a lever provided with an irregular slot in which the hammer moves, the said lever having its fulcrum substantially in line 35 with the line of movement of the firing-pin and the hammer. Such location of the hammer-controller adds greatly to the compactness of the gun, the simplicity of its parts, 40 cheapness of construction, and directness of action.

Figure 1 represents, in side elevation, the metal frame of a gun containing my improvements, the barrel and stock being omitted; 45 Fig. 2 a, top view thereof, the hammer being in section; and Fig. 3, a detail of the barrel-locking device and the connection between it and the hammer-controller.

The metal frame *a*, connected breech-block 50 *b*, hammer *c*, spring *d*, trigger *e*, guard *f*, and pivot or bolt *g*, upon which the usual gun-bar-

rel is pivoted at its lower side, are all as usual. When the rear of the barrel is thrown down into the space *h* to be placed in firing position it first acts upon and moves backward the barrel-locking device *i*, shown as a bolt acted upon by a spring, *j*, which keeps it thrown forward, and moves the said bolt backward, and holds it back until the recess made in the barrel to receive the said bolt is brought opposite the 60 said bolt, when the spring *j* throws it forward into the bolt-receiving recess in the barrel, which then locks the barrel securely in firing position. This bolt and the recess prepared for it in the barrel are not new.

I have provided the barrel-locking device with a pin or projection, *2*, to enter a slot in the pivoted arm or lever *k*, having a hub, 3, mounted in the frame *a*, (see Fig. 1,) with which, as herein shown, the hammer-controlling device *l* is connected by the screw *4*, making the lever *k* and device *l* practically as one piece, so that as the locking device *i* is moved the hammer-controlling device is also moved and made to occupy a position more or 75 less out of the line of movement of the hammer about its center 5.

It will be noticed that the hammer-controlling device *l* has its pivot in line with the direction of movement of the hammer, and in 80 line with the nipple *m*, in which is placed and held the centrally-located firing-pin, (shown in dotted lines,) it being provided, as usual, with a spring to move it backward when the hammer is lifted. The hammer-controller has an 85 opening made in it, which, at one side, is long and straight, as at *6*, while at its other side is a curved recess, *7*, forming a corner or stop, *8*.

When the locking device is in its most forward position, as it will be when the barrel is 90 locked in firing position, the hammer-controller occupies the position shown in full lines, and the hammer may be freely moved along the straight part *6* of the slot therein; but if the bolt is partly thrown or held back, the hammer-controller will be thrown aside, as in dotted lines, and the shoulder or stop part *8* of the controller will fall behind and prevent the upward movement of the hammer, which is necessary preparatory to exploding the cartridge.

The hammer-controlling device is made suf-

ficiently long to be used as a lever to move the bolt *i* forward and backward positively, when desired, and cause it to enter the usual recess prepared for it in the barrel, provided 5 (from dust, &c., in the space *h*) the barrel should be obstructed so that it did not descend quite low enough to let the bolt *i* fully enter the recess in the barrel, as described.

- I do not desire to limit my invention to a 10 hammer-controlling device shaped just as shown, or located just as shown, at the top or the center of the frame *a*, for it will be obvious to any one skilled in the art that the shape of the hammer-controller could be variously 15 modified and changed in position, and yet be so placed, through its connection with the locking device *i*, as to be moved by it to occupy a position to permit the hammer to be raised or prevent it being raised. If the bolt *i* should 20 be almost in position in the recess made for it in the barrel, the hammer, on being raised, will act upon the extreme corner *S* of the hammer-controller, and will turn the same sufficiently 25 to move the bolt fully forward.
- It is old to make a breech-loading gun having a longitudinally-sliding barrel provided with an aligned locking or clamping lever operated by the cocking of the hammer to insure the closing of the breech. This forms no 30 part of my invention, since the barrel-locking

bolt in my invention is separate from but jointed to its operating hammer-controller, and such hammer-controller absolutely prevents the fall or dropping of the hammer, whereas before the hammer could be cocked and dropped 35 at will irrespective of the position of the breech locking or clamping device.

I claim—

1. The combination of a barrel-locking bolt, *i*, a hammer and a hammer-controlling lever, *l*, slotted as shown, and arranged to be operated by or in unison with the said bolt and the hammer, the said lever preventing the lifting of the hammer while the locking-bolt is thrown or held back from proper engagement 45 with the barrel, substantially as described.

2. In a breech-loading gun, the combination, with the hammer, the barrel-locking bolt, its spring, arm *k*, and its hub *3*, of the connected lever *l*, slotted longitudinally and recessed, laterally and provided with a shoulder, 50 *S*, substantially as and for the purpose specified.

In testimony whereof I have signed my name to this specification in the presence of 55 two subscribing witnesses.

HENRY F. WHEELER.
